UNITED STATES PATENT OFFICE.

ISAAC V. ARVONEN, OF CALUMET, MICHIGAN.

DESIGN FOR A BRACELET.

SPECIFICATION forming part of Design No. 33,611, dated November 27, 1900.

Application filed April 14, 1900. Serial No. 12,940. Term of patent 7 years.

To all whom it may concern.

Be it known that I, ISAAC V. ARVONEN, a citizen of the United States, residing at Calumet, in the county of Houghton and State of Michigan, have invented and produced a new and original Design for Bracelets; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

15 Referring to the drawings, in which similar numerals of reference indicate corresponding parts in each of the views in which they occur, Figure 1 is a perspective view of a bracelet, showing my design. Fig. 2 is a perspective view of the upper portion on an enlarged scale.

The leading features of my design consist

in the shape, configuration, and ornamentation of a bracelet, as shown in the accompanying drawings, in which the body of the bracelet presents the appearance of a circular ribbon or narrow metallic band 2, having a knot 1 formed upon its upper portion. The knot has the appearance of being formed from two overlapping strips or portions 5 and 6 of the band, the ends of which curve downward and are joined to the main portion or body of the bracelet. An ornamental pendant 7, representing a cross, a heart, and an anchor, is secured to one of the overlapping portions of the knot.

25 30 35 What I claim is—

The design for a bracelet herein shown and described.

ISAAC V. ARVONEN.
